CALCULATING MACHINE

Original Filed May 28 1923 3 Sheets-Sheet 3

UNITED STATES PATENT OFFICE.

FREDERICK A. HART, OF NEW BRITAIN, CONNECTICUT, ASSIGNOR TO REMINGTON ACCOUNTING MACHINE CORPORATION, OF NEW YORK, N. Y., A CORPORATION OF NEW YORK.

CALCULATING MACHINE.

Application filed May 28, 1923, Serial No. 641,807. Renewed August 4, 1924.

To all whom it may concern:

Be it known that I, FREDERICK A. HART, citizen of the United States, and resident of New Britain, in the county of Hartford and 5 State of Connecticut, have invented certain new and useful Improvements in Calculating Machines, of which the following is a specification.

My invention relates to calculating machines and also to combined typewriting and calculating machines.

The main object of the invention, generally stated, is to provide means for preventing unnecessary movements of certain 15 parts of the construction which are ordinarily brought about by the travel of the main carriage, and thus reduce wear, strain and noise incidental to such unnecessary movements and decrease the liability of injury to the machine.

More specifically stated, one object of the invention is to provide improved means for preventing unnecessary movements of the auxiliary carriage, cross truck or jumping 25 totalizer without rendering it ineffective to move at proper intervals in the operation of the machine.

Another object of the invention, regarded more specifically than first stated above, is 30 to provide means for preventing unnecessary movements of the state control or change gear mechanism without preventing a shifting thereof at proper intervals in the operation of the machine.

To the above and other ends which will hereinafter appear, my invention consists 35 in the features of construction, arrangements of parts and combinations of devices set forth in the following description and particularly pointed out in the appended claims.

In the accompanying drawings, wherein like reference characters indicate corresponding parts in the different views,

Figure 1 is a fragmentary side elevation, 45 with parts omitted and parts in section, of a Remington accounting machine equipped with the devices of my invention.

Figure 2 is a detail fragmentary front 50 elevation of a portion of the same on a larger scale and with parts broken away and parts in section.

Figure 3 is a fragmentary front elevation 55 of a portion of the machine.

Figure 4 is a detail perspective view of

the pick-up beam and some of the associated mechanism.

Figure 5 is a view corresponding in part to Fig. 2, but showing the devices in the actuated position. 60

Figure 6 is a fragmentary top plan view of the same with parts in section.

I have shown my invention, in the present instance, embodied in a Remington accounting machine of the character disclosed in 65 the patent to John C. Wahl, No. 1,270,471, dated June 25, 1918, but have shown only so much of said machine as is necessary to arrive at an understanding of my invention in its embodiment therein. It should be 70 understood, however, that the invention is not restricted to its embodiment in such a machine but may be employed wherever found available in different makes of calculating machines. 75

The Remington accounting machine referred to above includes calculating mechanism attached to a Remington typewriting machine, the carriage of which latter has connected thereto a main calculator carriage 80 or truck, on which a series of so-called vertical totalizers are mounted. A cross foot or jumping totalizer is carried by an auxiliary carriage or cross truck, and automatically operating means are employed for repeatedly picking up and releasing the cross truck and allowing it to return to normal position during the travel of the typewriter and main carriage or truck across the machine in one direction. These forward and 85 backward movements of the cross truck are sometimes unnecessary, as will hereinafter appear. Ordinarily when the main carriage is given a continuous movement toward the left it results in picking up the cross truck 90 as each computing zone is approached and releasing it for return movement when the computing zone is passed, thus causing a series of forward and backward jumping movements of the cross truck with the wear, 95 strain, noise and increased liability of injury incidental to such unnecessary movements. By my present invention I overcome this difficulty by rendering the release of the cross truck by the automatically actuated pick-up mechanism ineffective to bring about an unnecessary jumping back or return of the cross truck to normal position. I accomplish this in the present instance under suitable conditions by automat- 100

ically throwing a detent or latch into engagement with the cross truck or a part operatively connected therewith. In the present instance this detent is controlled by, 5 and its actuation is incidental to, an operation of either of the ordinary release keys, and also is controlled by the handle of the line spacing mechanism, used also to return the main carriage, and by any of the tabulator keys. It follows, therefore, that any 10 of the ordinary means other than the printing keys and space key by which the travel of the main carriage is controlled is operative to render the detent effective and thereby prevent an unnecessary return 15 movement of the cross truck when it is released from its automatically actuated pick-up mechanism.

The Remington accounting machine referred to above also includes a state changing or change gear mechanism through which motion is transmitted to the register wheels of the cross totalizer, and which gears are often regulated to be shifted back and forth 25 by automatically actuated state changing or gear shifting means during the travel of the main carriage. It is sometimes unnecessary as when skipping computing zones without writing therein, to effect this 30 back and forth shifting of the gear change mechanism. I have, therefore, provided means which, in the present instance, are under control of the same devices that control the detent for the cross truck for rendering the automatically operating gear change 35 mechanism ineffective to shift. Said gear change mechanism will therefore, when set for automatic control, remain quiescent during the travel of the main carriage, when 40 such travel is controlled by any of said devices. So far as the means herein disclosed for controlling the cross truck against return movement are concerned, they are in the nature of improvements in the construction 45 disclosed in the application of John H. Barr, Serial No. 568,915, filed June 17, 1922.

In the Remington accounting machine of the character disclosed in the hereinbefore mentioned Wahl patent, the frame of the 50 typewriting machine comprises a base 9, corner posts 10 and top plate 11. The typewriter carriage, as usual, comprises a front cross bar 12, a rear cross bar 13, and end bars 14 and 15. The carriage is mounted to 55 travel over the top plate and supports a cylindrical plate 16, and is impelled in the direction of its feed by the usual spring drum, not shown. The carriage is controlled in its step-by-step letter space movements 60 by the usual escapement mechanism which may be said to include the feed pinion 17. A feed rack 18 is carried by the carriage and pivoted thereto at 19; the usual spring (not shown) returning the feed rack into engagement with the feed pinion 17.

A carriage release key 20 is provided on the forward end of a release lever 21 pivoted at 22 on the right-hand end bar 15 of the carriage. The rear end of this lever I have bifurcated at 23 to receive a reduced end 70 24 of the feed rack 18, and form an interlocking connection therewith. A corresponding carriage release key 25 is provided at the opposite side of the machine at the forward end of a lever 26, corresponding to 75 the release lever 21 and I have also connected it by an interlocking connection with the feed rack 18.

The usual decimal tabulator mechanism employed in the Remington accounting machine comprises a column stop bar 27 carrying adjustable column stops 28 and supported by bracket arms 29 that project rearwardly from the carriage. Co-operative with the column stops is a series of denominational stops 30, each forming a forwardly extending projection on a lever 31, pivoted at 32 on a tabulator frame 33. Said frame is secured by screws 34 to the top plate of the machine, and also to the base by means 90 not shown. The lower end of each tabulator stop lever 31 is connected to a push rod 35, carrying a tabulator key 36 at the forward end thereof. Each rod has one end of a contractile spring 37 connected thereto at 38. 95 The opposite end of each spring 37 is connected to a frame by which the forward ends of push rods are supported and guided, and which is detachably secured to the base 9.

In addition to projecting each stop 30 into the path of the column stops, the actuation of each tabulator key 36 effects a release of the carriage. Thus, each stop rod 35 carries a collar 39 held fast on the rod by 100 a screw 40. Each of these collars constitutes an abutment that coacts with a universal release bar 41 supported at its ends by arms 42 pivoted on a rod 43; the lower edge portion of release bar 41 being slotted 105 to enable the push rods to extend therethrough. Each arm 42 is connected to a rearwardly extending link 44, connected at its rear end to a depending crank arm 45 on a rock shaft 46. This shaft also carries a 110 crank arm 47, pivoted at 48 to an upwardly extending link 49, which in turn is pivoted at 50 to the frame 51 of a carriage releasing device. Said frame is pivoted at 52 on a bracket 53 secured to the top plate 11 of the 115 machine frame. The releasing frame carries a journal 54 in which a shaft of the carriage retarding device turns; the forward end of said shaft carrying a pinion 55, and the rear end of the shaft carrying a 120 retarding device operative in the drum 56. The actuation of a tabulator key is effective therefore to rock the frame 51 and lift the pinion 55. This results in throwing the pinion 55 into mesh with the feed rack 125 130

18 and lifting said rack to disengage it from the feed pinion 17. The carriage is then free to travel to the left until arrested by the approaching column stop 28 coacting 5 with the decimal stop 30 that has been projected into the path thereof by the same actuation of the tabulator key 36. When pressure is released from the actuating key 36, it will be returned to normal position, 10 together with the projected stop 30, by its spring 37, and a spring 57 returns the universal release bar and the parts controlled thereby to normal position.

The said Remington accounting machine 15 also includes a main calculator carriage or truck comprising a bar 58 suitably guided and supported and connected at its ends to travel with the typewriter carriage. Such connection is effected by bracket arms 59 20 secured to the end portions of the bar 58, and each provided with an upright slot 60 that receives the cylindrical part of a shou- 25 dered and headed screw 61. Each screw 61 is secured to the depending forward end of a bracket arm 62, secured to the typewriter carriage. The bar 58 carries one or more so-called vertical totalizers which are detachable therefrom and may be adjusted to different points along said bar. Usually 30 a plurality of such totalizers are employed, as many as thirty being employed in some instances in long carriage machines. In Fig. 3, I have shown four such totalizers designated respectively by the reference numerals 35 63, 64, 65 and 66. Each totalizer comprises a frame which contains the usual equipment including register wheels 67 and indicating dials 68, which latter display their numerals 40 at sight-openings 69 in the frame of the totalizer. A key controlled master wheel 70 operates on the register wheels 67 as they are brought successively into mesh with the master wheel by the step-by-step movement of the typewriter carriage and the corresponding movement of the main truck or carriage which carries the vertical totalizers. Motion is transmitted from the numeral keys 45 71 of the typewriting machine to the master wheel 70 through the usual actuator or transmitting means, which I have not deemed it necessary to illustrate. It will be understood, however, that such transmitting means include the usual change gear construction by which the master wheel may 50 be disconnected, or may be caused to turn in one direction or the other for causing corresponding movement of the register wheels and dials for addition or subtraction. This change gear construction is controlled 55 by hand at the will of the operator and may be set at will for either "Add" or "Subtract" or "Disconnect", but for the purposes of the present invention it is deemed unnecessary to enter into a specific consideration

of such mechanism, all of which is described 65 in the Wahl Patent No. 1,270,471.

The Remington accounting machine of the character disclosed in said Wahl patent also includes cross totalizing mechanism, which will now be described. Only so much 70 of this mechanism is shown as is necessary to arrive at an understanding of the features of my present invention in their co-operation therewith.

The supporting frame for the auxiliary 75 carriage or cross truck includes a fixed bar 72, having oppositely disposed grooves or tracks for the reception of anti-friction balls 73, as shown in Fig. 1. These balls are also received in oppositely grooved 80 tracks in a casting or bar 74, which in the main constitutes the cross truck, or jumping auxiliary carriage. This cross truck is connected at 75 to one end of a contractile spring 76, fastened at its opposite end 85 to a fixed pin 77 on the fixed bar 72, and having its looped portion passing around a pulley 76^a, as shown in Fig. 2. The power of this spring is exerted to return the cross truck to the right to the limit of its movement independently of the main carriage when the cross truck is freed from the main truck or carriage, as will hereinafter appear. The cross truck carries one or more 90 cross totalizers one such totalizer 78 being employed in the present instance. However, one form of the present invention was devised for use in a machine which employs a plurality of such cross totalizers, and for the purpose of the present invention it is 95 immaterial how many such cross totalizers are employed. Said cross totalizer is constructed like the vertical totalizer, with the dials, sight-openings, and register wheels including the wheels 79. These last mentioned wheels correspond to the wheels 67 in the vertical totalizers, and are brought successively into mesh with a master wheel 80 as the cross truck advances step-by-step with the main carriage when a vertical 100 totalizer is passing through the computing zone.

The key controlled actuating mechanism for the master wheel 70 of the vertical totalizers in the Remington accounting machine of the character shown in said Wahl patent also operates the master wheel 80. A change gear mechanism including a shiftable gear wheel 81 also is employed for the cross totalizer, such change gear mechanism being adapted to be shifted automatically 105 when a vertical totalizer enters the computing zone. The means whereby the automatic shifting of the gear change mechanism for the cross totalizer is effected will 110 now be described in detail.

When it is desired to have the gear change mechanism for the cross totalizer shifted

automatically from the normal, or say "Add" position, to either the "Subtract" or "Disconnect" position as a vertical totalizer enters the computing zone in its movement 5 with the main carriage, such totalizer will be provided with a cam 82 of greater or less depth, depending on its function to control the gear shift mechanism of the cross totalizer for "Subtract" or "Disconnect." Should 10 the operator desire to have the machine arranged for "Add" in the cross totalizer 78 when a given vertical totalizer is in the computing zone, then the cam 82 on the corresponding vertical totalizer is detached; or 15 if it be an adjustable cam, it is adjusted to inoperative position. Each cam 82 coacts with a follower 83 as a vertical totalizer enters the computing zone and depresses it a greater or less distance depending on the 20 character of the cam, i. e., whether it be a cam of the greatest depth for setting the change gear for "Subtract" or a cam of less depth set to change the gear for "Disconnect." The follower 83 is in the nature of 25 a roller supported by a laterally projecting pin on the free end of a crank arm 84, mounted on the forward end of a rock shaft 85. As a vertical totalizer passes out of the computing zone, the follower 83 and the 30 parts controlled thereby are returned to normal position by a spring.

The intermediate connections between the shaft 85 and the change gear mechanism of the cross totalizer will now be described.

Referring first to Fig. 2, it should be understood that this figure shows the gear change mechanism of the cross totalizer, or the parts which automatically control it, in their normal positions. Said view shows a cam 82 about to coact with the follower 83 to bring about a depression thereof and automatically shift the change gear mechanism as the vertical totalizer which carries said cam 82 is about to enter the computing zone. Fig. 5 shows the positions of the parts after the change gear mechanism has been shifted, and the vertical totalizer carrying the active cam 82 is about to pass out of the computing zone.

Referring to these two figures and to Fig. 6, which shows the parts disposed as they appear in Fig. 5, it will be seen that the rock shaft 85, which carries the follower 83, has its rear bearing in a fixed support 88, the same being the main frame casting of the calculating mechanism, and that said shaft extends through said support beyond the rear side thereof. The rear end of this rock shaft has a three-armed lever or member 89 secured thereto. One arm 90 of this member is connected to a contractile spring 91 which is the spring hereinbefore referred to as the restoring spring for this whole train of gear shift mechanism. A second

arm 92 on the member 89 coacts with a stop 65 pin 93, to limit return movement of the member 89 and the parts connected therewith to normal position. The third arm 94 of said member 89 has pivoted thereto, at 70 95, two parallel links 96 and 97 of like formation, each formed with a V-shaped notch 98 in the upper side thereof. These links are maintained spaced apart and are fixedly united to move together by suitable means such as a shouldered rivet 99. The bottom 75 of the V-shaped notch is in the nature of a seat for a pin 100. This pin is carried by and projects laterally from the upper end of a lever 101, fulcrumed on a pivot 102, carried by a hand controlled link 103 and supported in the usual manner by a fixed bracket, not shown. The pin 100 has a hub 104 provided with a flange 105, spaced from the upper end of lever 101 to form 80 a circumferential groove so that it may be received and guided in a slot 106 in a fixed supporting plate 107. The lower end of the lever 101 is provided with an angular slot 108 through which projects a pin 109 carried by a crank arm 110. This crank arm is fixed 85 to the rear end of a rock shaft 111, which receives a bearing in the support 88. The forward end of this rock shaft carries an upwardly projecting crank arm 112, pivotally connected at 113 to one end of a link 90 95 114. The opposite end of this link is pivoted at 115 to a lever 116, fulcrumed at 117 on a bracket arm secured to the supporting frame. The lower end of the lever 116 is pivoted at 118 to a slide 119 by which the 100 change gear mechanism is shifted.

As fully described in the Wahl patent, hereinbefore referred to, there are two shiftable gears, the rear one being journaled on and sliding with the rod 119. The gear 81 shown in the drawing, is the forward gear which slides in the opposite direction to the rod 119.

From the foregoing description it will be understood that, assuming the parts to be normally in the position shown in Fig. 2, the entrance of a vertical totalizer in the computing zone will bring the companion cam 82 into co-operation with the follower 83, and depress it to the position shown in Fig. 5. The effect of this is to rock the lever 116 through the intermediate train of connections from the Fig. 2 to the Fig. 5 position and automatically shift the change gear of the cross totalizer; shifting the gear 81 from the full to the dotted line position in Fig. 2. When the cam 82 runs off of follower 83, the parts move back to addition position.

In said Remington accounting machine 125 if the operator should desire to compute in, say, the last computing zone without actuating the preceding vertical totalizers this

is ordinarily accomplished by depressing either of the ordinary carriage release keys moving the carriage by hand, say, from the extreme right-hand position to bring the 5 right-hand totalizer, say 66, to the computing zone. This same result may be accomplished by successively operating one of the tabulator keys 36 until the vertical totalizer 66 is brought to the computing zone. The 10 effect in either case is that the cams 82 on all of the preceding vertical totalizers 63, 64 and 65 will cause successive operations of the gear change mechanism of the cross totalizer. When a large number of vertical 15 totalizers are employed this unnecessary repeated back and forth operation of the gear change or gear shift mechanism, whenever the carriage is moved as stated, causes undue wear on the parts with the possibility 20 of injuring the mechanism by reason of the rapidity and force of the operations, and also results in the production of an unnecessary amount of noise. It will be understood, moreover, that this repeated 25 unnecessary operation of the gear shifting mechanism of the cross totalizer takes place during the return movement of the carriage, with the same liability of injury to the machine. Such return movement of the carriage 30 is usually effected with the aid of a combined line spacing and carriage return handle 120 which is connected to a rock shaft 121 and is returned to normal position on the carriage by a spring 122, see 35 Fig. 6.

It is one of the purposes of my invention to eliminate this unnecessary automatic operation of the change gear mechanism during forward and back traveling movements of the main carriage, when such movements are effected in the manner set forth or in any manner except in the ordinary step-by-step feed of the carriage under control of the letter or numeral keys, 40 or the usual letter space key, as will hereinafter more clearly appear.

The means disclosed in the present instance for preventing unnecessary back and forth movement of the automatic shifting 45 means for the change gear of the cross totalizer, is automatically controlled by the operation of any tabulator key 36, by either of the carriage release keys 20 or 25 and by the handle 120 in the manner which will 50 now be pointed out.

The release keys 20 and 25 are extended forwardly further than they are ordinarily, but each is provided on the right-hand edge thereof with the usual upwardly turned 55 flange 123 that assists the operator in moving the carriage to the right after the release key is first depressed to release the carriage. The outer face of each flange 123 is curved and I utilize each such face to 60 coact with a cam to actuate the controlling

mechanism. Thus, the outer face of the flange 123 on the key 20 coacts with the inclined edge 124 of a cam member 125. A second inclined face 126 on said cam member rests on the right-hand edge of the associated bracket 62. The cam member 125 has a carrying arm or off-set extension 127 pivoted at 128 to a horizontally disposed plate, bar or controlling member 129 that extends substantially throughout the length 70 of the main calculator carriage or truck in the rear of the bar 58 thereof and forward of the fixed support 88. This controlling member 129 while it is connected to travel with the typewriter carriage and the main truck, is mounted in a suitable manner to receive a movement relatively to the main truck. In the present instance the member 129 is provided with inclined slots 130 at 75 different points throughout the length thereof, which slots receive the reduced ends 131 of studs 132. The member 129 is held in place on the reduced ends of the studs by headed screws 131^a screwed at their inner ends into tapped openings in studs 132. The forward threaded ends of said studs are received in tapped openings in the truck bar 58, and said studs thus provide supports by which the member 129 is carried by the bar 58 of the main truck. A 80 contractile spring 133 is connected at one end to a pin 134 projecting forward from the member 129, the other end of said spring being connected to a pin 135 that projects rearwardly from the bar 58. The 85 force of the spring is exerted to move the member 129 on the main truck to the left, and by reason of the inclined slots 130 such movement likewise compels the member to receive an upward movement to the normal 90 position shown in Fig. 2. When, however, the release key 20 is depressed such movement cams the member 125 to the right and causes a corresponding movement of the member 129, which also results in a downward movement of said member 129 to the 95 operated positions shown in Fig. 5. A roller 136 extends beneath the lower edge of the controlling member 129, said roller being carried by a stud 137 that projects forwardly from a horizontally disposed lever 138. The right-hand end of this lever is pivoted at 139 on the fixed support 88, and is received in a cut-out portion of the front 100 face of said support, as indicated at 140 in 105 Fig. 6. The lever 138 is pressed upwardly by a spring 141, anchored at its lower end by a screw 142 to the support 88. The 110 power of this spring is exerted to maintain the roller 136 in contact with the lower edge 115 of the controlling member 129, and to lift the lever 138 when the member 129 is moved to its normal elevated position. Depending 120 from the lever 138 is a projection 143 that terminates in an extension 144 that 125 130

projects to the left. Said extension 144 underlies an extension or contact 145 on a latch, catch, pawl, detent, locking or holding device 146. Said device is pivoted at 6 its right-hand end, as indicated at 147, and in the present instance is in the nature of a gravity catch. An engaging projection 148 on said catch is adapted to extend behind and in the path of a pin 149 on the link 10 114 of the automatically actuated gear change shift mechanism, as indicated in Fig. 5, or to be held out of the path of movement of said pin 149, as indicated in Fig. 2, which shows the parts in normal position.

15 Let it be assumed that the typewriter carriage is at the extreme right, and that the operator desires to bring the extreme right-hand vertical totalizer 66 to the computing zone without registering in any of the preceding vertical totalizers. The operator 20 may depress the carriage release key 20, thereby lowering the controlling member 129 and forcing down the lever 138 against the force of its spring 141. The effect of this 25 is to permit the gravity pawl or catch 146 to be lowered to the effective position. The feed rack 18 having been released by the depression of the release key 20, the operator may now move the carriage to the left and 30 when the cam 82 on the first vertical totalizer 63 reaches the computing zone, it will depress the follower 83, and automatically shift the gear change mechanism from the Fig. 2 to the Fig. 5 position. During such 35 movement of the parts, the link 114 will move from right to left, causing the pin 149 to be brought against the rear beveled face of the projection 148, thereby lifting the gravity pawl 146. When said pin passes 40 the projection 148 the gravity pawl drops to effective position with the front face of the projection 148 engaging behind the pin 149, preventing a return movement of the link 114 and a return of the follower 83 from its depressed position. This results 45 in locking the change gear mechanism, and the entire train of connections from said mechanism to the follower, against return movement, as shown in Fig. 5. It follows 50 therefore that the follower 83 will be maintained against return movement at the lowest point of its depression, and out of the path of any of the cams 82 on the succeeding vertical totalizers as long as the operator 55 maintains pressure on the release key 20. The parts of the automatically shifting change gear mechanism will therefore remain quiescent instead of being shifted back and forth as each vertical totalizer passes through 60 the computing zone. When the totalizer 66 reaches said zone the operator releases pressure on the release key 20, the bar 129 and lever 138 are restored by their springs 133 and 141 to their normal upper positions, drawing latch 146 out of engagement with

pin 149 and freeing the change gear mechanism. Said mechanism then assumes whatever position is appropriate to the column in use, depending on whether or not the particular vertical totalizer has a cam 82, 70 and if it has, how deep a cam it is. The operator then proceeds to operate the numeral keys to register a number in the totalizers 66 and 78. In the drawing, totalizer 66 is shown with a subtract cam, and the member would therefore be registered negatively in totalizer 78. When said totalizer passes through the computing zone, all parts of the gear shifting mechanism will be returned to normal position. 80

I have provided corresponding means at the other side of the machine whereby the same results are accomplished should the operator depress the left-hand release key 25, instead of the right-hand release key. 85 Thus, the outer right-hand curved face of the flange 123, on the key 25, coacts with the inclined face 150 of a cam member 151. This member rests upon the associated bracket 62 and is provided with an offset 90 extension 152, pivoted at 153 to the controlling member 129. It has hereinbefore been explained that both the levers which carry the release keys 20 and 25 have an interlocking connection with the feed rack 18, 95 and it follows therefore that both keys are connected through said rack to move together. Both keys operating on their respective cam members to shift the controlling member 129 to the right and downwardly, from the normal position, it follows that an actuation of either key 20 or 25 will produce the same results explained above. 100

After a number has been set up in the last totalizer 66, as described, and the operator 105 desires to return the carriage to, say, the extreme right, this may be done by maintaining pressure on either release key and moving the carriage to the right as previously explained. The pressure thus maintained 110 on a release key holds the follower 83 in a depressed position as previously described, and maintains it, and the parts controlled thereby, out of action until all of the vertical totalizers have passed to the right over 115 the follower 83, and the carriage is returned to the extreme right-hand position. It will be understood, therefore, that the gear shift mechanism is maintained out of action during return movement of the carriage, as well 120 as during the free forward movement thereof.

Sometimes the carriage is returned to the right by the combined carriage return and line spacing handle 120. In order therefore that the carriage may be returned with the aid of this handle without unnecessarily operating the gear shift mechanism, I have provided means whereby an actuation of said handle automatically moves the carriage 130

trolling member 129 from the Fig. 2 to the Fig. 5 position. This effects the same results that are attained by depressing either of the carriage release keys 20 or 25. The 5 handle controlled means referred to comprises a crank arm 154 secured to and extending downwardly from the rock shaft 121 to which the handle 120 is secured. This crank arm in its movement to the 10 right from the normal position coacts with a pin 155 which projects rearwardly from the extension 127 of the right-hand cam member 125. In returning the carriage with the aid of the handle 120, pressure exerted 15 on the latter is effective to turn its rock shaft 121 before the carriage is moved to the right. This movement of the rock shaft carries the crank arm 154 from the full to the dotted line position in Fig. 5 20 and moves the controlling member 129 to the position shown in this figure. When the rock shaft reaches the limit of its turning movement the carriage will start to move to the right. The pressure of the operator's 25 hand on the handle is maintained until the carriage is fully returned to the right. Consequently such pressure will hold the controlling member 129 and the parts controlled thereby in the Fig. 5 position until 30 the return of the carriage is completed. When this is accomplished the operator releases the handle 120 and its spring 122 will return it to normal position, permitting the controlling member 129 and the parts controlled thereby to return to normal position. 35

It has been hereinbefore explained that an actuation of any of the tabulator keys 36 is effective to lift the feed rack 18, and by reason of the connection between said rack and both carriage release keys 20 and 25 this will effect a depression of the latter. It follows, therefore, that an actuation of any tabulator key will move the controlling member 129 from the Fig. 2 to the Fig. 5 40 position in the same manner as though said controlling member were actuated by either of the carriage release keys, or the line spacing handle and said controlling member will be maintained in its operative position as long as the operator maintains pressure on the actuated tabulator key. When it is released and returns to normal position the release keys 20 and 25, the controlling member 129 and the parts controlled thereby will return to normal position. 50

From the foregoing description it will be understood that automatically operating means are provided for throwing the automatic gear shift mechanism out of action on the operation of either of the carriage release keys 20 or 25, on actuation of the line spacing and carriage return handle 120, and on the actuation of any of the tabulator keys 36. 55

I have stated that in addition to automatically throwing the change gear mechanism out of operation, I also provide automatically actuated means whereby the unnecessary forward and back jumping movements of the cross totalizer are eliminated, with the undue wear, injury and noise which are apt to result from such unnecessary jumping movements of the cross totalizer and its truck. This construction will now be described, but before describing these features of my invention it is necessary to describe the usual construction embodied in the Remington accounting machine as it is disclosed in said Wahl patent, with sufficient detail 70 to arrive at an understanding of my invention in combination therewith. 75

Automatically operating connecting means between each vertical totalizer and the cross truck or carriage are provided for intermittently picking up the cross carriage and releasing it, for alternate forward and backward movements during a single travel of the main truck or carriage in one direction. This mechanism is disclosed in Fig. 4. The 80 right-hand side plate of each vertical totalizer is formed with an engaging projection 156, which is adapted to coact with an upwardly extending hook-like projection or tooth 157 on a so-called pick-up beam 158. A laterally projecting headed screw stud 159, fixed to the beam 158 is received in a short horizontally disposed bearing slot 160 in a bracket arm 161, secured to the cross truck 74. This construction enables the beam 158 to receive a pivotal movement on the bracket, and also affords a limited relative sliding movement between the two against the action of a contractile buffer spring 162, connected at one end to a pin 100 163 carried by the beam 158, and at its other end to the bracket arm 161. It will be observed that the force of the spring is directed in a line above the stud 159, and therefore tends to turn the beam around the center of said stud and elevate the inner hook-carrying-end of the beam, and also tends to maintain the stud seated at the right-hand end of the slot 160. This last mentioned function of the spring is to provide a cushion between each connected vertical totalizer and the cross truck as the latter is picked up by the former, especially in the rapid movement of the carriage under the action of the tabulator keys, and when 110 the carriage is moved by hand. 115

A forwardly projecting pin 164 extends from the pick-up beam 158 and projects through a large opening 165 in a pick-up guard 166, to be hereinafter more specifically described. This pin 164 is provided with a guide flange 167 which coacts with the guard 166 at the front side thereof. 125

The pin 164, after passing through the opening 165 in the pick-up guard, extends 130

into a slot 168 in a fixed plate 169. A part of the lower wall of the slot 168 is formed by the upper edge of an auxiliary plate 170 adapted to be adjusted along the plate 169, and secured in place thereon by screws 171. The upper edge of the plate 170 has a depression 172 therein, which when the parts are in normal position is beneath the pin 164. This permits the pin 164 to move down into the depression as the engaging projections 156 on the vertical totalizers move successively over the beveled face of the tooth 157 and depress the pick-up beam in the backward travel of the main carriage. The slot 168 throughout all other parts thereof is of a width which corresponds substantially to the diameter of the pin 164, and the walls of the slot therefore restrain the pin against free up and down movement. The left-hand portion of the slot 168 is formed with a cam 173, with which the pin 164 coacts as the pick-up beam is carried along with the main carriage by a projection 156 on a vertical totalizer. The effect of engaging the cam 173 is to move the pin 164 and the hook-carrying-end of the beam down, thus disengaging the hook 157 from the totalizer, and enabling the cross truck and the beam to be returned to the right independently of the main truck or carriage. The spring 76 is effective to bring about this independent return movement of the cross truck and the parts connected therewith. In addition to the spring 162 for elevating the beam 158 there is provided the usual lever 174 pivoted at 175 on a fixed pivot and connected at one end to a spring 176. The contact nose 177 of this lever is arranged beneath and is adapted to bear against the lower edge of the pick-up beam 158, and tends to resist the downward disengaging movement thereof. A forwardly projecting ear 178 on the lever 174, coacts with the under edge of the fixed plate 169 and limits the upward movement of the nose 177. The bottom edge of the pick-up beam 158 is so formed that it remains out of contact with the nose 177 of the lever when the pin 164 engages the cam 173, as shown in Fig. 4, to release the pin from the engaged vertical totalizer, so that, when said beam is depressed, it does not have the resistance of the spring 176 to overcome.

The pick-up guard 166, hereinbefore referred to, is provided to automatically coact at its free end 179 with the right-hand face of the projection 156 on a vertical totalizer when the hook or tooth 157 engages the opposite side of said projection, and thus form an interlock that prevents a relative movement between the main truck and the cross truck in either direction of travel.

A complete detail description of the construction and operation of the pick-up guard is deemed unnecessary, except to point out

that it is automatically actuated and operates in conjunction with the pick-up beam to insure the proper positioning of the cross truck in a decimal position corresponding to that of a vertical totalizer, when the latter is in the computing zone. This may be better understood when it is pointed out that the pick-up guard 166 is pivoted on the stud 159 and is moved to its elevated engaging position by a spring 180. When the cross truck returns, and the pick-up beam moves back to normal position, a cam 181, see Fig. 4, on the guard 166 engages a pin 182 which is in the path of the cam and is carried by a fixed plate 170. This engagement of the cam with the pin causes the guard member 166 to be lowered at its free end out of the path of the projections 156. When, however, the pick-up beam is engaged by the projection 156 and moved to the left, the cam member 181 is moved away from the fixed pin 182. This enables the guard to be elevated by its spring 180 and the end 179 of the guard to be positioned to the right of the projection 156 engaged by the hook 157. When, however, the hook 157 is cammed down out of engagement with the projection 156, as hereinbefore described the pin 164 carries the guard 166 down with it.

It will be understood that ordinarily in the operation of the machine, as a vertical totalizer, say, 63, approaches the computing zone to bring a wheel 67 thereof into mesh with the master wheel 70, the pick-up beam 158 will be engaged by the projection 156 on said totalizer 63, causing the cross truck and the totalizer 78 to travel in unison with the main truck or carriage. As said totalizer 63 passes out of the computing zone, and beyond the master wheel 70, the pin 164 reaches the cam 173 and releases the pick-up beam, thereby enabling the cross truck and the totalizer 78 to be returned to the right by the spring 76. This intermittent forward and back movement of the cross truck and the totalizer takes place as each vertical totalizer passes through the computing zone, even when no actuation of the vertical totalizers is effected. This, therefore, results in unnecessary forward and back movements of the cross truck and totalizer, with the consequent unnecessary wear, liability of injury thereto and the production of a clattering noise especially under the rapid movements of the main carriage by hand, or under control of the tabulator. Let it be assumed for example that the main carriage is in the extreme right-hand position and the operator desires to operate only the last or fourth totalizer 66. It has hereinbefore been explained that this may be effected by depressing either of the carriage release keys 20 or 25 and moving the carriage down to the proper position by hand, as is usually the case. Or as is sometimes the case, the

result may be effected by operating the proper tabulator key, in the instance supposed, four times, thereby bringing the fourth totalizer 66 by successive jumps of 5 the main carriage into proper position to be actuated. In the said Remington accounting machine, when the carriage is moved by hand to the desired point, and as the first vertical totalizer approaches the computing zone, 10 the cross truck will be automatically picked up and carried with the main carriage until said vertical totalizer passes out of said zone, when the cross truck will be released and jump back to normal position. The alternate automatic picking up and releasing of 15 the cross truck for return movement thereof is repeated as each vertical totalizer passes through the computing zone. Substantially the same result is brought about in said machine when the tabulator keys are successively operated to bring the last totalizer 66 to the computing zone. In the specific example shown there will be six unnecessary forward and backward movements of the 20 cross truck to bring the totalizer 66 into proper position without actuating any of the preceding vertical totalizers. It should be remembered however, that as many as, say, thirty vertical totalizers are sometimes employed on long carriage Remington accounting machines, and that to bring the last totalizer to proper position as supposed above would result in some fifty-eight unnecessary rapid forward and back jumping movements 25 of the cross truck at each such selection of the last vertical totalizer for use. But by my present invention these unnecessary jumping movements of the cross truck are eliminated, thus saving a great amount of 30 unnecessary wear on the parts, liability of injury thereto and the elimination of the clattering noise due to such jumping of the truck. This result is attained in the present instance by the mere addition of a latch, 35 locking device, pawl or detent 183 to the automatically controlled lever 138. Said pawl is pivoted at 184 to a depending arm 185 on said lever, and is returned to and maintained in normal position with reference to said lever by a contractile spring 40 186, connected at one end to the arm 185 and at the other end to a projection 187 on said pawl. A laterally extending lug 188 is provided on the pawl, and said lug overlies 45 the horizontal portion of the arm 185 to coact therewith, and limit the pivotal movement of the pawl under the force of its spring 186. In the present instance the lower part of the arm 185 is bent as shown 50 in Fig. 1 to bring the dog 183 into an inclined position to engage properly with a convenient part of the bracket 161. The detent 183 is intended under certain conditions to engage the cross truck or any suitable part attached thereto or operatively 55 connected therewith. In the present instance the engaging nose 189 of the pawl or detent 183 indicated in Fig. 2 is normally out of the path of the bracket arm 161, fixed to the cross truck and on which the pick-up beam 70 158 is mounted, as will be understood from an inspection of Fig. 1. When the bar 129 is depressed as hereinbefore described the lever 158 will be lowered from the Fig. 2 to the Fig. 5 position as hereinbefore explained, carrying the detent 183 down with it. This brings the lower inclined edge 190 of the detent into the path of the bracket arm 161 and the carriage having been released will be advanced. Before the first 75 vertical totalizer 63 reaches the computing zone the cross truck will be picked up and advanced with the main carriage. During this advance of the cross truck, the bracket 161 will coact with the inclined edge 190 on 80 the detent and deflect it upwardly around its pivot 184, and against the force of the spring 186. As soon as the bracket 161 passes the free end of the detent, the spring 186 will snap the detent back to engaging position 85 with the engaging nose 189 thereof to the right of and in a position to engage the right-hand face of the bracket arm 161 as shown in Fig. 5, thus preventing a return 90 movement of the cross truck as long as the 95 detent remains in this position, that is to say, as long as pressure is maintained on a release key, which is during the entire forward travel of the carriage necessary to bring the vertical totalizer 66 to the computing zone. When this position has been attained the operator releases pressure on the depressed release key, and the controlling member 129, the lever 138 and the detent 183 are returned to normal position, 100 shown in Fig. 2, where the detent no longer offers an obstruction to the return movement 105 of the cross truck. However, with the main carriage in the position indicated, ready to register in the last totalizer 66, the projection 156 thereon will be positioned where the advanced pick-up beam 158 will coact therewith as soon as the operator releases the depressed release key 20 or 25, thereby 110 preventing a return movement of the cross truck to normal position. As the carriage advances in registering a number in the last totalizer 66 the cross truck will be advanced 115 with it and as the totalizer 66 passes out of the computing zone the pick-up beam will be 120 automatically released and the cross truck will be returned to normal position. It will be seen therefore that the cross truck was advanced and returned to normal position only once, although the carriage carried all 125 of the vertical totalizers through the computing zone and registered a number in the last totalizer 66. The same thing would occur under like conditions no matter how many vertical totalizers are employed. If, for ex- 130

ample, thirty totalizers be employed and the same character of entry is to be made, there would be a single forward movement of the cross truck and a single backward movement 5 thereof to normal position instead of sixty forward and backward movements, as would be the case ordinarily.

Should the carriage be in the extreme right-hand position and the operator prefers to bring the last totalizer 66 to the computing zone without registering in the preceding vertical totalizers, with the aid of a tabulator key, this may be done as follows:

The operator actuates the proper tabulator 15 key 36 preferably of a low order four times, thereby bringing the fourth totalizer 66 by successive jumps of the main carriage into proper position to be actuated. Ordinarily 20 the consequence of jumping the main carriage in the manner described is to alternately pick up and release the cross truck for free return movement to normal position for each jump of the main carriage, and there would be six unnecessary forward and 25 back movements of the cross truck in the example specified, or fifty-eight such unnecessary movements if thirty totalizers were employed under the same conditions. It will be understood, moreover, that ordinarily 30 the pick-up of the cross truck in the manner indicated is effected while the main carriage is running free during a tabulating operation and often when the carriage has run a considerable distance before the pick-up of 35 the cross truck is effected, and at times when the cross truck is running free in the opposite direction. For example, in skipping columns the cross truck, when released from a vertical totalizer that is at the time passing 40 out of the computing zone will jump all the way back to its normal position if the vertical totalizers are spaced some distance apart. This unnecessary jumping back of the cross truck results in unnecessary wear 45 and noise. If on the other hand the totalizers are close together then when the cross truck jumps to the right it is arrested by the pick-up beam engaging the lug 156 of the next oncoming totalizer. As said oncoming 50 vertical totalizer is then moving rapidly toward the left and the cross truck is moving rapidly to the right the resulting blow on the comparatively frail parts is apt to injure or strain the construction, such for example 55 as by breaking off the projection 157.

In the present construction I overcome these difficulties by automatically throwing the detent 183 into action at each operation 60 of any tabulator key to hold the cross truck in its forward position as long as pressure is maintained on a tabulator key. It has been explained that when the feed rack 18 is elevated by the operation of a tabulator key to release the carriage, such movement 65 of the rack through the interlocking con-

nnection at 23, 24 effects a depression of both release keys 20 and 25. This is effective to bring about a lowering of the controlling member 129 and the parts controlled thereby from the Fig. 2 to the Fig. 5 position. This 70 drops the detent 183 into effective position in the same manner as if the operation was effected by a release key. As the carriage moves forward to bring the first totalizer 75 63 to the computing zone, the cross truck is picked up and moved to effective position in a corresponding decimal position, the detent 183 by this time being rendered effective to hold the cross truck against return movement. When the tabulating movement 80 of the carriage is completed the operator releases the actuated tabulator key. This enables the parts controlled by the tabulator key to return to the normal Fig. 2 position 85 and withdraws the detent 183 from the path of the arm 161. However, the carriage in the tabulating jump carried the totalizer 63 forward to the computing zone but not far enough to release the pick-up beam, which release occurs when the totalizer passes out 90 of said zone. Therefore, the connection of the pick-up mechanism will be maintained and the cross truck will not return. The next operation of a tabulator key will advance the carriage and carry the totalizer 95 63 through the computing zone, bringing the totalizer 64 to said zone. The effect of this is to release the cross truck from the pick-up mechanism, but at the time of such release the cross truck is held in forward position 100 by the detent 183. When the actuated tabulator key is released for the second time the detent will no longer hold the cross truck, but at this time the carriage has advanced the second totalizer 105 64 to the computing zone, and in a position where the pick-up mechanism will coact with the cross truck. The pick-up mechanism will therefore prevent a return movement of the cross truck to normal position, though it may at times 110 drop back two or three spaces, or far enough to permit the pick-up mechanism to engage the totalizer, in the present instance the totalizer 64. At this time the main truck is at rest and the blow on the lug 156 is a 115 slight one. So on it is with the remaining totalizers until the last vertical totalizer 66 is brought to the computing zone, a number is registered in this totalizer, and it passes out of the computing zone. The cross truck will then be automatically released from control of the pick-up mechanism and will 120 return to normal position.

From the foregoing it will be understood that during the successive operations of the 125 tabulator key to move the carriage so as to convey all of the vertical totalizers except the last through the computing zone, and to bring the last vertical totalizer to the computing zone and register a number therein, 130

there is but one forward movement of the cross truck from the normal to the advanced position indicated in Fig. 5, and that there is but one return movement of the cross truck to normal position.

- 5 It will be observed, moreover, that the rendering of the gear change mechanism ineffective to shift, and the locking of the cross truck against movement to normal position, 10 are both automatically controlled by the controlling member 29 and that said member is automatically controlled by the release keys 20 and 25, by the line space, by the carriage return handle 120 and by all 15 of the tabulator keys 36. It will be seen, therefore, that all of the ordinary means, by which the forward and back travel of the carriage may be effected, except the letter space movement thereof by the printing 20 keys and the letter space key, are effective to automatically control the cut-out of the gear change mechanism and the lock for the cross truck.

While I have described in detail one form 25 of construction embodying the present invention I am aware that the invention may be embodied in various forms, and that certain features thereof may be employed without others. For example, while it may be 30 desirable to silence the gear change mechanism against automatic actuation, valuable results are attained by merely silencing the cross truck, or holding it against return movement as described, and vice versa. 35 Then again, while it may be desirable to automatically control either or both of said silencing means by the various keys and the handle 120 as stated, from certain aspects of my invention it is sufficient to control either 40 or both of said means from any of said parts, as defined in the following claims.

When I refer herein to "state" change or controlling means, or employ like expressions, I thereby intend to designate means 45 whereby parts of the construction are regulated to bring about in a register either addition, subtraction or a neutral condition in which no actuation thereof is effected, as is well understood in the art.

50 What I claim as new and desire to secure by Letters Patent is:—

1. In a calculating machine, the combination of a carriage, register wheels, actuating means for said register wheels, state controlling means automatically controlled by the carriage, a release key carried by the carriage for freeing it from control of its escapement mechanism, and means controlled by an actuation of said release key 55 for controlling said state controlling means.

2. In a calculating machine, the combination of a carriage, register wheels, actuating means for turning said register wheels, state controlling means automatically shifted under control of the carriage, a release key

carried by the carriage for freeing it from control of its escapement mechanism, and means controlled by said release key for preventing certain shifting movements of said state controlling means.

3. In a calculating machine, the combination of a carriage, a release key carried thereby, a jumping totalizer, automatically operating means for effecting a plurality of forward and backward movements of said jumping totalizer for a complete movement of said carriage in one direction, and means controlled by said release key for preventing a return movement of said jumping totalizer to normal position.

4. In a calculating machine, the combination of a carriage, register wheels, change gears for turning said register wheels, automatically operating gear changing means actuated by the travel of the carriage, a carriage release key carried by the carriage, and means controlled by said release key for rendering said gear changing means ineffective to change the gears unnecessarily.

5. In a calculating machine, the combination of a carriage, a plurality of release keys carried by the carriage one at each end thereof, a jumping totalizer, automatically operating means for effecting forward and backward movements of the jumping totalizer during the travel of the carriage in one direction, and means controlled by both of said release keys for preventing a return movement of the jumping totalizer as long as either release key is maintained depressed.

6. In a calculating machine, the combination of a carriage, register wheels, key controlled means for turning said register wheels including automatically operating 105 changeable means for turning the register wheels in one direction or the other or for disconnecting the turning means from said register wheels, a carriage release key carried by the carriage and means controlled 110 by an actuation of said release key for preventing repeated operation of said automatically operating changeable means.

7. In a calculating machine, the combination of a carriage, register wheels, change gears for turning said register wheels, automatically operating gear changing means actuated by the travel of the carriage, a carriage release key, tabulator mechanism including a tabulator key, and means controlled by an actuation of said release key and also by said tabulator key for rendering said gear changing means ineffective to change the gears repeatedly at one run of the carriage.

8. In a calculating machine, the combination of a carriage carrying a plurality of vertical totalizers, a release key carried by said carriage, a jumping totalizer, automatically operating means for picking up 130

the jumping totalizer as a vertical totalizer approaches the computing zone and for releasing it for return movement when the computing zone is passed, and means controlled by said release key for preventing the return movement of said jumping totalizer.

9. In a calculating machine, the combination of a carriage, register wheels, actuating means for turning said register wheels, state controlling means automatically shifted by the travel of the carriage, a carriage return handle, and means controlled by said handle for preventing repeated shifting of said state controlling means during a single run of the carriage.

10. In a calculating machine, the combination of a carriage, register wheels, key controlled means for turning said register wheels including automatically changing means for causing the register wheels to be turned in one direction or the other or for disconnecting the turning means from said register wheels, a carriage release key carried by the carriage, a tabulator key, and means controlled by an actuation of said release key and also by an actuation of said tabulator key for preventing unnecessary operation of said automatically changing means.

11. In a calculating machine, the combination of a carriage carrying a plurality of vertical totalizers; a release key carried by said carriage; a jumping totalizer; automatically operating means for picking up the jumping totalizer as a vertical totalizer approaches the computing zone and for releasing it for return movement when the computing zone is passed; and means controlled by said release key for preventing a return movement of said jumping totalizer, said last mentioned means comprising a detent maintained ineffective when the release key is in the normal position and moved to effective position by the act of depressing the release key and maintained in effective position as long as the release key remains depressed.

12. In a calculating machine, the combination of a carriage, register wheels, change gears for turning said register wheels, automatically operating gear changing means actuated by the travel of the carriage, a carriage release key carried by the carriage, and means controlled by said release key for rendering said gear changing means ineffective to change the gears as long as said release key is held in its actuated position and for restoring the gears to the control of their automatically operating changing means by the return of said release key to normal position.

13. In a calculating machine, the combination of a carriage, register wheels, actuating means for turning said register wheels, state

controlling means, automatically operating means for shifting said state controlling means, a release key carried by the carriage for freeing said carriage from control of its escapement mechanism, tabulating mechanism including a tabulator key, and means controlled by said release key and also by said tabulator key for preventing unnecessary operation of said automatically operating shifting means.

14. In a calculating machine, the combination of a carriage carrying a plurality of vertical totalizers; a release key carried by said carriage; a jumping totalizer; automatically operating means for picking up the jumping totalizer as a vertical totalizer approaches the computing zone and for releasing it for return movement when the computing zone is passed; means controlled by said release key for preventing a return movement of said jumping totalizer, said last mentioned means comprising a detent maintained ineffective when the release key is in the normal position and moved to effective position by the act of depressing the release key and maintained in effective position as long as the release key remains depressed, and a part operatively connected with said jumping totalizer and with which said detent is thrown into and out of co-operative relation, the detent when effective enabling said part to move in one direction but preventing its movement in the opposite direction.

15. In a calculating machine, the combination of a carriage, register wheels, change gears for turning said register wheels, automatically operating gear changing means actuated by the travel of the carriage, a carriage release key, tabulator mechanism including a tabulator key, and means controlled by an actuation of said release key and also by said tabulator key for preventing repeated shifting of said gears as long as either of said keys is held in its actuated position and for restoring the gears to control of their automatically operating changing means when the actuated key returns to normal position.

16. In a calculating machine, the combination of a carriage, register wheels, actuating means for turning said register wheels, state controlling means for changing the actuating means to turn the register wheels for plus or minus, automatically operating means for shifting said state controlling means, a release key carried by the carriage for freeing it from control of its escapement mechanism, a combined carriage return and line spacing handle, and means controlled by said release key and also by said handle for rendering said automatically operating shifting means ineffective to cause repeated shifting of said state controlling means.

17. In a calculating machine, the combina-

- tion of a carriage, a release key therefor, a controlling member carried by the carriage and controlled by said release key, a detent carried by a fixed part of the machine and controlled by said controlling member, a jumping totalizer, automatically operating means for moving said totalizer forward and backward during the travel of the carriage in one direction, and means operatively connected with said totalizer and with which said detent coacts to prevent a return movement of the jumping totalizer to normal position when the release key is maintained depressed.
- 15 18. In a calculating machine, the combination of a carriage, change gears, automatically operating gear changing means actuated by the travel of the carriage, line spacing mechanism, and means controlled thereby for taking said gears out of control of their automatically operating changing means.
19. In a calculating machine, the combination of a carriage, a release key therefor, a controlling member carried by the carriage and controlled by said release key and extending longitudinally substantially throughout the width of the carriage, a detent carried by a fixed part of the machine and controlled by said controlling member at any point in the travel of the carriage, a jumping totalizer, automatically operating means for moving said totalizer forward and backward during the travel of the carriage in one direction, and means operatively connected with said totalizer and with which said detent coacts to prevent a return movement of the jumping totalizer to normal position when the release key is maintained depressed.
- 40 20. In a calculating machine, the combination of a carriage, register wheels, actuating means for turning said register wheels, state controlling means, automatically operating means for shifting said state controlling means, a release key carried by the carriage for freeing it from control of its escapement mechanism, a combined carriage return and line spacing handle, tabulating mechanism including a tabulator key, and means controlled by said line spacing and tabulator keys and also by said handle for rendering said automatically operating shifting means ineffective to act repeatedly during one run of the carriage.
- 55 21. In a calculating machine, the combination of a carriage, register wheels, means including change gears for imparting motion to said register wheels, automatically operating gear changing means controlled by the travel of the carriage, a handle for returning the carriage, and means controlled by said handle for preventing repeated operation of said automatically operating gear changing means.
- 60 22. In a calculating machine, the combination of a carriage, register wheels, key controlled means for turning said register wheels including automatically operating changeable means for turning the register wheels in one direction or the other, or for disconnecting the turning means from said register wheels, a handle for returning the carriage, and means controlled by said handle for preventing repeated operation of said automatically operating changeable means.
- 70 23. In a calculating machine, the combination of a carriage; a release key carried thereby; a jumping totalizer; automatically operating means for effecting a plurality of forward and backward movements of said jumping totalizer for a complete movement of said carriage in one direction; and means controlled by said release key for preventing a return movement of said jumping totalizer to normal position; said last mentioned means comprising a detent rendered effective by the depression of said release key and a part operatively connected with said jumping totalizer and with which said detent is adapted to coact to prevent a return movement of the jumping totalizer to normal position.
- 80 24. In a calculating machine, the combination of a carriage, register wheels, actuating means for turning said register wheels, automatically operating state controlling means for changing the actuating means to turn the register wheels for plus or minus, said state controlling means including contacts on the carriage and a shiftable device on the frame of the machine, a release key carried by the carriage for freeing the carriage from control of its escapement mechanism, and means controlled by said release key for maintaining said shiftable device out of the path of said contacts on the carriage.
- 90 25. In a calculating machine, the combination of a carriage, register wheels, change gears for turning said register wheels, automatically operating gear changing means controlled by the travel of the carriage, a carriage release key, a line spacing handle by which the carriage may be returned, and means controlled by said release key and also by said handle for rendering said automatically operating gear changing means ineffective as long as the operator maintains either said key or handle in its actuated position and for rendering said gear changing means effective when the actuated key or handle returns to normal position.
- 100 26. In a calculating machine, the combination of a carriage, register wheels, key controlled means for turning said register wheels including automatically operating changeable means for turning the register wheels in one direction or the other, or for disconnecting the turning means from said register wheels, a carriage release key carried by the carriage, a combined line spacing

and carriage return handle, a tabulator key, and means controlled by an actuation of said carriage release key and also by said handle and said tabulator key whereby an actuation of either of said keys or said handle prevents repeated operation of said automatically operating changeable means.

27. In a calculating machine, the combination of a carriage; register wheels; change gears for turning said register wheels; automatically operating gear changing means controlled by the travel of the carriage; a carriage release key; a line spacing handle by which the carriage may be returned; tabulator mechanism including a tabulator key; and means controlled by said tabulator key, handle, and release key for preventing repeated operation of the automatically operating gear changing means.

28. In a calculating machine, the combination of a carriage, register wheels, actuating means for turning said register wheels, state controlling means for changing the actuating means to turn the register wheels for plus or minus, automatically operating means for shifting said state controlling means including contacts on the carriage and a shiftable device on the frame of the machine, a combined carriage return and line spacing handle, and means controlled by said handle for maintaining said shiftable device out of the path of said contacts on the carriage.

29. In a calculating machine, the combination of a main carriage, a release key therefor, an auxiliary carriage, automatically operating means for effecting forward and backward travel of the auxiliary carriage during a single travel of the main carriage in one direction, tabulator mechanism including a tabulator key, and means controlled by said tabulator key and also by said release key for rendering said automatically operating means ineffective to bring about a backward movement of said auxiliary carriage to normal position while either key is in operated position.

30. In a calculating machine, the combination of a main carriage, register wheels, key controlled means for turning said register wheels including automatically operating changeable means for turning the register wheels in one direction or the other or for disconnecting the turning means from said register wheels, a carriage release key, a jumping carriage, automatically operating connecting means for effecting forward and backward travel of said jumping carriage during a single travel of the main carriage in one direction, and means controlled by said release key for preventing repeated operation of said automatically operating changeable means and of said automatically operating connecting means.

31. In a calculating machine, the combination of a carriage, register wheels, actuating means for turning said register wheels, automatically operating state controlling means for changing the actuating means to turn the register wheels for plus or minus including contacts on the carriage and a shiftable device on the frame of the machine, a release key carried by the carriage for freeing the carriage from control of its escapement mechanism, a combined carriage return and line spacing handle, and means controlled by said release key and also by said handle for maintaining said shiftable device out of the path of said contacts on the carriage.

32. In a calculating machine, the combination of a main carriage, an auxiliary carriage, automatically operating means for alternately picking up said auxiliary carriage and releasing it for independent return movement during the travel of the main carriage in one direction, a release key carried by said main carriage for freeing it from control of its escapement mechanism, and means controlled by said release key for preventing the independent return movement of said auxiliary carriage to normal position.

33. In a calculating machine, the combination of a main carriage, an auxiliary carriage, automatically operating means for effecting forward and backward travel of the auxiliary carriage during a single travel of the main carriage in one direction, line spacing mechanism including a handle by which the main carriage may be returned, and means controlled by an actuation of said handle for rendering said automatically operating means ineffective to bring about a backward movement of said auxiliary carriage to normal position.

34. In a calculating machine, the combination of a carriage, register wheels, actuating means for turning said register wheels, automatically operating state controlling means for changing the actuating means to turn the register wheels for plus or minus including contacts on the carriage and a shiftable device on the frame of the machine, a release key carried by the carriage for freeing the carriage from control of its escapement mechanism, a combined carriage return and line spacing handle, tabulator mechanism including a tabulator key, and means controlled by said release and tabulator keys and also by said handle for maintaining said shiftable device out of the path of said contacts on the carriage.

35. In a calculating machine, the combination of a main carriage, key controlled totalizers carried thereby, a spring returned jumping carriage, a totalizer carried thereby, automatically operating mechanism for alternately picking up said jumping car-

riage for movement in unison with the main carriage and for releasing the jumping carriage for independent return movement to normal position under the action of its spring during a single travel of the main carriage in one direction, a release key carried by the main carriage for freeing it from control of its escapement mechanism, and means controlled by said release key for holding the jumping carriage from independent return movement to normal position as long as pressure is maintained on said release key and for freeing the jumping carriage for independent return movement when said release key returns to normal position.

36. In a calculating machine, the combination of a main carriage, key controlled totalizers carried thereby, a spring returned jumping carriage, a totalizer carried thereby, automatically operating mechanism for alternately picking up said jumping carriage for movement in unison with the main carriage and for releasing the jumping carriage for independent return movement to normal position under the action of its spring during a single travel of the main carriage in one direction, a release key carried by the main carriage for freeing it from control of its escapement mechanism, and a normally ineffective detent which is controlled by said release key and which is moved into the path of said jumping carriage or a part that is operatively connected to move in unison therewith and prevents the return movement of said jumping carriage as long as pressure is maintained on said release key, the return of the release key to normal position enabling said detent to be withdrawn from the path of the part with which it coacts, thus enabling the return of the jumping carriage to normal position.

37. In a calculating machine, the combination of a main carriage, an auxiliary carriage, automatically operating means for effecting repeated forward and backward travel of the auxiliary carriage during a single travel of the main carriage in one direction, register wheels, change gears for turning said register wheels, automatically operating gear changing means actuated by the travel of the carriage, and a member operable at will for simultaneously rendering both of said automatically operating means ineffective, one to change the gears and the other to bring about a backward return of the carriage to normal position.

38. In a calculating machine, the combination of a main carriage, escapement mechanism therefor, an auxiliary carriage, automatically operating means for effecting repeated forward and backward travel of the auxiliary carriage during a single travel

of the main carriage in one direction, register wheels, change gears for turning said register wheels, automatically operating gear changing means controlled by the travel of the carriage, releasing means for freeing the main carriage from control of its escapement mechanism, and means controlled by said releasing means for rendering both of said automatically operating means ineffective, one to change the gears and the other to bring about a backward return movement of the auxiliary carriage to normal position.

39. In a calculating machine, the combination of a main carriage, escapement mechanism therefor, an auxiliary carriage, automatically operating means for effecting forward and backward travel of the auxiliary carriage during a single travel of the main carriage in one direction, register wheels, change gears for turning said register wheels, automatically operating gear changing means controlled by the travel of the main carriage, a release key for the main carriage, and means controlled by said release key for rendering both of said automatically operating means ineffective as long as said release key is held in the actuated position and for restoring said auxiliary carriage and gears to the control of their respective automatically operating means when the operator releases pressure on said release key.

40. In a calculating machine, the combination of a main carriage, escapement mechanism therefor, an auxiliary carriage, automatically operating means for effecting forward and backward travel of the auxiliary carriage during a single travel of the main carriage in one direction, register wheels, change gears for turning said register wheels, automatically operating gear changing means controlled by the travel of the main carriage, tabulator mechanism including a tabulator key, and means controlled by said tabulator key for rendering both of said automatically operating means ineffective while said key is in operated position.

41. In a calculating machine, the combination of a main carriage, escapement mechanism therefor, an auxiliary carriage, automatically operating means for effecting forward and backward travel of the auxiliary carriage during a single travel of the main carriage in one direction, register wheels, change gears for turning said register wheels, automatically operating gear changing means controlled by the travel of the main carriage, a handle for returning the main carriage, means controlled by said handle for rendering said automatically operating gear changing means ineffective for unnecessary operation, and automatically

- operating means for preventing repeated forward and backward travel of the auxiliary carriage.
42. In a calculating machine, the combination of a main carriage, escapement mechanism therefor, an auxiliary carriage, automatically operating means for effecting forward and backward travel of the auxiliary carriage during a single travel of the main carriage in one direction, register wheels, change gears for turning said register wheels, automatically operating gear shifting means controlled by the travel of the main carriage, a release key for the main carriage, tabulator mechanism including a tabulator key, and means controlled by both of said keys for rendering both of said automatically operating means ineffective at an actuation of either key.
43. In a calculating machine, the combination of a main carriage, escapement mechanism therefor, an auxiliary carriage, automatically operating means for effecting forward and backward travel of the auxiliary carriage during a single travel of the main carriage in one direction, register wheels, change gears for turning said register wheels, automatically operating gear changing means controlled by the travel of the main carriage, line spacing mechanism including a handle effective to return the main carriage, a release key for the main carriage, tabulator mechanism including a tabulator key, and means controlled by both keys and by said handle for rendering both said automatically operating means ineffective at an actuation of either of said keys or of the handle.
44. In a calculating machine, the combination of a main carriage, a controlling member carried thereby, a cross truck, automatically operating means for causing said cross truck to move forward and back to normal position during the travel of the main carriage in one direction, means controlled by said controlling member for preventing such back or return movement of the cross truck, and automatically operating means for actuating said controlling member.
45. In a calculating machine, the combination of a main carriage, a controlling member carried thereby, a cross truck, automatically operating means for causing said cross truck to move forward and back to normal position during the travel of the main carriage in one direction, means fixed against travel with the carriage for preventing such back or return movement of the cross truck and which are controlled by said controlling member at any point in the travel of the carriage, and automatically operating means for actuating said controlling member.
46. In a calculating machine, the combination of a main carriage, a controlling member carried thereby, a cross truck, a cross totalizer carried thereby, change gear mechanism for actuating said cross totalizer, automatically operating means for shifting said change gear mechanism during the travel of the main carriage, means controlled by said controlling member for throwing said automatically operating shifting means out of operation, and automatically operating means for actuating said controlling member.
47. In a calculating machine, the combination of a main carriage, a controlling member carried thereby, a cross truck, a cross totalizer carried thereby, change gear mechanism for actuating said cross totalizer, automatically operating means carried in part by the main carriage and in part by the frame of the machine for shifting said change gear mechanism during the travel of the main carriage, controlling means fixed against traveling movement with the main carriage for rendering said automatically operating shifting means for the change gear mechanism ineffective, said controlling means being operated by said controlling member at any point in the travel of the main carriage, and means for automatically actuating said controlling member.
48. In a calculating machine, the combination of a main carriage, a controlling member carried thereby, a cross truck, automatically operating means for causing said cross truck to move forward and back to normal position during the travel of the main carriage in one direction, means controlled by said controlling member for preventing such back or return movement of the cross truck, a carriage release key, and means controlled by said key for actuating said controlling member.
49. In a calculating machine, the combination of a main carriage, a controlling member carried thereby, a cross truck, automatically operating means for causing said cross truck to move forward and back to normal position during the travel of the main carriage in one direction, means controlled by said controlling member for preventing such back or return movement of the cross truck, a tabulator key, and means controlled by said key for actuating said controlling member.
50. In a calculating machine, the combination of a main carriage, a controlling member carried thereby, a cross truck, a cross totalizer carried thereby, change gear mechanism for actuating said cross totalizer, automatically operating means for shifting said change gear mechanism during the travel of the main carriage, means con-

trolled by said controlling member for throwing said automatically operating shifting means out of operation, a key for releasing the carriage, and means controlled 5 by said key for actuating said controlling member.

51. In a calculating machine, the combination of a main carriage, a controlling member carried thereby, a cross truck, a 10 cross totalizer carried thereby, change gear mechanism for actuating said cross totalizer, automatically operating means for shifting said change gear mechanism during the travel of the main carriage, means controlled 15 by said controlling member for throwing said automatically operating shifting means out of operation, a handle for returning the carriage, and means controlled by said handle for actuating said controlling 20 member.

52. In a calculating machine, the combination of a main carriage, a controlling member carried thereby, a cross truck, automatically operating means for causing said 25 cross truck to move forward and back to normal position during the travel of the main carriage in one direction, means controlled by said controlling member for preventing such back or return movement of 30 the cross truck, a cross totalizer carried by said cross truck, change gear mechanism for actuating said totalizer, automatically operating means for shifting said change gear mechanism, means controlled 35 by said controlling member for throwing said automatically operating shifting means out of operation, and automatically operating means for actuating said controlling member.

40 53. In a calculating machine, the combination of a main carriage, a controlling member carried thereby, a cross truck, automatically operating means for causing said cross truck to move forward and back to 45 normal position during the travel of the main carriage in one direction, means controlled by said controlling member for preventing such back or return movement of the cross truck, a cross totalizer carried by 50 said cross truck, change gear mechanism for actuating said cross totalizer, automatically operating means for shifting said change gear mechanism, means controlled by said controlling member for throwing said automatically operating shifting means out of operation, a key for releasing the carriage, and means controlled by said key for actuating 55 said controlling member.

54. In a calculating machine, the combination of a main carriage, a controlling member carried thereby, a cross truck, automatically operating means for causing said cross truck to move forward and back to normal position during the travel of the 60 main carriage in one direction, means controlled by said controlling member for preventing such back or return movement of the cross truck, a cross totalizer carried by said cross truck, change gear mechanism for actuating said cross totalizer, automatically operating means for shifting said change gear mechanism, means controlled by said controlling member for throwing said automatically operating shifting means out of operation, a key for releasing the carriage, and means controlled by said key for actuating said controlling member.

trolled by said controlling member for preventing such back or return movement of the cross truck, a cross totalizer carried by said cross truck, change gear mechanism for actuating said cross totalizer, automatically operating means for shifting said change gear mechanism, means controlled by said controlling member for throwing said automatically operating shifting means out of operation, a tubulator key, and means controlled by said tabulator key for actuating said controlling member.

55. In a calculating machine, the combination of a main carriage, a controlling member carried thereby, a cross truck, automatically operating means for causing said cross truck to move forward and back to normal position during the travel of the main carriage in one direction, means controlled by said controlling member for preventing such back or return movement of the cross truck, a cross totalizer carried by said cross truck, change gear mechanism for actuating said cross totalizer, automatically operating means for shifting said change gear mechanism, means controlled by said controlling member for throwing said automatically operating shifting means out of operation, a handle for returning the carriage, a carriage release key carried by the carriage, a tabulator key, and means controlled by said keys and by said handle for actuating said controlling member, whereby the operation of either of said keys or said handle is effective to actuate said controlling member.

56. In a combined calculating and typewriting machine in which a cross truck automatically travels back and forth during a single travel of the typewriter carriage in one direction, the combination of a release key carried by the typewriter carriage, a cam member controlled by said release key, and a locking member controlled by an actuation of said cam member and movable thereby into effective position to prevent a return movement of the cross truck to normal position.

57. In a combined calculating and typewriting machine in which a cross truck automatically travels back and forth during a single travel of the typewriter carriage in one direction, the combination of a release key carried by the typewriter carriage, a feed rack also carried by the carriage and having an interlocking connection with said release key so that a movement of either one will effect a movement of the other, means controlled by said release key for locking the cross truck against return movement to normal position, and tabulator mechanism including a key and means controlled thereby for moving said feed rack and freeing the carriage from control of its escapement mechanism, whereby an

operation of either the carriage release key or the tabulator key renders said locking means effective.

58. In a combined calculating and type-writing machine in which a cross truck automatically travels back and forth during a single travel of the typewriter carriage in one direction, the combination of a release key carried by the typewriter carriage, a cam member controlled by said release key, a locking member controlled by an actuation of said cam member and movable thereby into effective position to prevent a return movement of the cross truck to normal position, a feed rack carried by said carriage and having an interlocking connection with said release key so that a movement of either one will effect a movement of the other, and tabulator mechanism including a tabulator key and means controlled thereby for moving said feed rack for freeing the carriage from control of its escapement mechanism, whereby an operation of either the carriage release key or the tabulator key is effective to free the carriage and render said locking means effective.

59. In a calculating machine, the combination of a main carriage, a cross truck that moves back and forth during a single travel of the main carriage in one direction, a release key carried by said main carriage for freeing it from control of its escapement mechanism, a locking device carried by the fixed frame of the machine and movable thereon into effective position to lock the cross truck against return movement to normal position, and a controlling bar carried by and movable on said carriage and co-operative with said locking device to control its movement into and out of effective position, said controlling member being controlled by said release key.

60. In a calculating machine, the combination of a main carriage, a cross truck that moves back and forth during a single travel of the main carriage in one direction, a release key carried by said main carriage for freeing it from control of its escapement mechanism, a locking device carried by the fixed frame of the machine and movable thereon into effective position to lock the cross truck against return movement to normal position, a controlling bar carried by and movable on said carriage and co-operative with said locking device to control its movement into and out of effective position, said controlling member being controlled by said release key, tabulator mechanism including a tabulator key and means controlled thereby for moving said feed rack and thereby shifting the release key and said parts controlled thereby to move the locking device to effective position.

61. In a calculating machine, the combination of a main carriage, a cross truck that moves back and forth during a single travel of the main carriage in one direction, a release key carried by said main carriage for freeing it from control of its escapement mechanism, a locking device carried by the fixed frame of the machine and movable thereon into effective position to lock the cross truck against return movement to normal position, a controlling bar carried by and movable on said carriage and co-operative with said locking device to control its movement into and out of effective position, said controlling member being controlled by said release key, a feed rack having an interlocking connection with said release key so that the movement of either one will cause a movement of the other, and tabulator mechanism including a tabulator key and a rack releasing device controlled thereby, whereby a movement of either the carriage release key or the tabulator key is effective to release the carriage and move said locking device to effective position.

62. In a calculating machine, the combination of a main carriage, a cross truck that moves back and forth during a single travel of the main carriage in one direction, a release key carried by said main carriage for freeing it from control of its escapement mechanism, a locking device carried by the fixed frame of the machine and movable thereon into effective position to lock the cross truck against return movement to normal position, a cam member controlled by said release key, a controlling bar controlled by said cam member and carried by and movable on said carriage and co-operative with said locking device to control its movement into and out of effective position, a feed rack having an interlocking connection with said release key, and tabulator mechanism including a tabulator key and means controlled thereby for moving said feed rack and thereby shifting the release key and said parts controlled thereby to move the locking device to effective position.

63. In a calculating machine, the combination of a main carriage, a cross truck, a totalizer carried thereby, actuating means for said totalizer including automatically shifting change gear mechanism, a carriage release key carried by said carriage, a cam member controlled by said release key, and means controlled by said cam member for holding said change gear mechanism against operation.

64. In a calculating machine, the combination of a main carriage, a cross truck, a totalizer carried thereby, actuating means for said totalizer including automatically shifting change gear mechanism, a carriage release key carried by said carriage, a con-

trolling bar carried by said carriage and movable thereon by the actuation of said release key, and means controlled by said controlling member for holding said change gear mechanism out of operation.

65. In a calculating machine, the combination of a main carriage, a cross truck, a totalizer carried thereby, actuating means for said totalizer including automatically shifting change gear mechanism, a carriage release key carried by said carriage, a feed rack, an interlocking connection between the feed rack and said release key so that the movement of either one will move the other, a controlling bar carried by the carriage and movable thereon by said release key, means controlled by said controlling bar for maintaining said change gear against automatic shifting movement, and tabulator mechanism comprising a tabulator key and means controlled thereby for moving said feed rack and through said interlocking connection bringing about a maintenance of the gear change mechanism against automatic shifting.

66. In a calculating machine, the combination of a main carriage, a release key therefor, a cross truck, automatically operating means for moving the cross truck back and forth during a single travel of the carriage in one direction, a totalizer carried by the cross truck, actuating means therefor including automatically shifting change gear mechanism, and automatically operating means controlled by said release key for throwing out of action said automatically shifting change gear mechanism and preventing a return of the cross truck to nor-

mal position, the same comprising a controlling bar on the carriage and controlled by said release key, a detent for the cross truck controlled in its movement to effective position by said controlling bar, and a detent for the change gear mechanism also controlled in its movement to effective position by said controlling bar.

67. In a calculating machine, the combination of a main carriage, a release key therefor, a cross truck, automatically operating means for moving the cross truck back and forth during a single travel of the carriage in one direction, a totalizer carried by the cross truck, actuating means therefor including automatically shifting change gear mechanism, and automatically operating means controlled by said release key for throwing out of action said automatically shifting change gear mechanism and preventing a return of the cross truck to normal position, the same comprising a controlling bar on the carriage and controlled by said release key, a lever carried by the fixed frame of the machine and controlled by said controlling bar, a detent for the cross truck, and a detent for the change gear mechanism, the movement of both of said detents into and out of effective position being controlled by said lever.

Signed at the borough of Manhattan, city of New York, in the county of New York and State of New York, this 24th day of May, A. D. 1923.
